(57) **CLAIM**

The ornamental design of a land clearing tool assembly with a depth control ring and a drum interface, as shown and described.

DESCRIPTION

FIG. 1 is a front, right, exploded, perspective view of a land clearing tool assembly and a depth control ring;

FIG. 2 is a rear, right, exploded, perspective view thereof;

FIG. 3 is a front, left, exploded, perspective view thereof;

FIG. 4 is a rear, left, exploded, perspective view thereof;

FIG. 5 is a right, exploded view thereof;

FIG. 6 is a top, exploded view thereof;

FIG. 7 is a front, right, assembled, isometric view of the land clearing tool assembly and a depth control ring of FIG. 1;

FIG. 8 is a rear, right, assembled, isometric view thereof;

FIG. 9 is a front, left, assembled, isometric view thereof;

FIG. 10 is a rear, left, assembled, isometric view thereof;

FIG. 11 is a right, assembled view thereof; and,

FIG. 12 is a top, assembled view thereof.
